UNITED STATES PATENT OFFICE

93,462

DESIGN FOR A ROLLER-SKATE

William D. Ferris, Sterling, Ill., assignor to
Hustler Corporation, Sterling, Ill., a corporation
of Illinois

Application May 23, 1934, Serial No. 51,896

Term of patent 3½ years

To all whom it may concern:

Be it known that I, WILLIAM D. FERRIS, a citizen of the United States, and resident of Sterling, in the county of Whiteside and State of Illinois, have invented a new, original, and ornamental Design for a Roller-Skate, of which the following is a specification, reference being had to the accompanying drawing, forming a part thereof.

Fig. 1 is a side elevation of a roller-skate, showing my new design.

Fig. 2 is a front elevation of the roller-skate shown in Fig. 1.

The device of my design comprises the several elements shown in solid black lines in the drawing, combined with the roller-skate shown in dotted lines. The dominant characteristics of my design consist of the elements positioned one over each of the skate rollers, in the manner indicated in Fig. 2 of the drawing.

I claim:

The ornamental design for a roller-skate, as shown and described.

WILLIAM D. FERRIS.
